A. H. BALLARD

LIQUID FUEL BURNING APPARATUS

Filed Dec. 12, 1923

Inventor:
Arthur H. Ballard.
by Henry Booth, James Barnes,
Alviss

UNITED STATES PATENT OFFICE

ARTHUR H. BALLARD, OF BOSTON, MASSACHUSETTS, ASSIGNOR TO BALLARD OIL BURNING EQUIPMENT COMPANY, OF BOSTON, MASSACHUSETTS, A CORPORATION OF MASSACHUSETTS.

LIQUID-FUEL-BURNING APPARATUS.

Application filed December 12, 1923. Serial No. 680,158.

This invention relates to oil burning apparatus and more particularly to controlling devices for automatically regulating the fuel supply.

5 The invention will be best understood by reference to the following description when taken in connection with the accompanying illustration showing one specific embodiment thereof, while its scope will be more particularly pointed out in the appended claims.

In the drawings,—

Fig. 1 is a front elevation of an apparatus embodying one form of the invention;

15 Fig. 2 is a sectional elevation on the line 2—2 in Fig. 1 showing the air pressure control for the oil supply valve;

Fig. 3 is a central sectional elevation on an enlarged scale showing the burner; and

20 Fig. 4 is a side elevation of the burner and its connections.

Referring to the drawings and to the embodiment of the invention there illustrated, I have shown the same applied to a steam boiler 5 adapted for steam heating purposes, 25 but the invention as to many of its features is applicable to other uses. Herein the burner 7 is located just outside of the combustion chamber, the casing of the latter having an opening through the burner adapted to project an atomized mixture of air and liquid hydrocarbon.

The burner may be of any suitable type, but herein it is shown as provided with an interior oil supply tube 9 communicating at 35 its rear end with an oil supply conduit 11, its opposite end being closed except for a number of radial ports 13. The tube 9 is contained within a surrounding air tube 15 communicating with the air supply pipe 17. The 40 oil delivered through the lateral orifice 13 is met at right angles by the air delivered through the air tube 15 and is carried thereby into a mixing chamber 19. There the two are commingled and pass through perforations 21 into a second mixing chamber 23, whence the air and oil thoroughly commingled are delivered through the orifice 25 of the burner nozzle into the fire or combustion chamber of the heater. The constantly burning pilot light 27 fed from a gas supply is located in front of the burner so as to ignite the fuel as soon as the supply valve is opened.

In a burner of this type it is desirable to maintain a substantially constant relation

between the oil pressure and the air pressure and preferably a substantially constant pressure for the feed of the oil. For this purpose there is provided the main oil tank or reservoir 29 from which oil is drawn through the pipe 31 and the oil filter 33 by means of the gear pump or other oil supplying device 35. The oil tank is preferably vented to the atmosphere through the vent pipe 37. To best cooperate with the control device herein provided, oil is conveyed by the pump 35 through the pipe 39 to a supply chamber elevated above the burner, where a supply of oil is maintained at a substantially constant level and from which the burner is supplied through the oil supply pipe 11.

The supply chamber is herein shown as embodied in the T connection 41 which is connected laterally with the oil feed pipe 39 and at its bottom with the oil supply pipe 11. At the top of the T there is attached by means of the nipple 43 the Y connection 45, the remaining branch of the Y being connected to the overflow pipe 47, the latter extending laterally and downwardly and connected to the top of the reservoir 29 to discharge the overflow from the elevated chamber back into the said reservoir. The top of the Y is preferably closed by the plug 49 so that the chamber therein is closed to the atmosphere except through the overflow pipe, reservoir and vent pipe 37.

The pump 35 which is driven from the electric motor 51 is designed to deliver oil to the elevated supply chamber in excess of the maximum requirements of the burner, so that the chamber is kept filled to a point determined by the location of the overflow pipe. The overflow pipe is preferably given a capacity in excess of that required for the maximum overflow so as to prevent any tendency of the oil pressure to fluctuate due to a siphon action arising from the choking or damming up of the viscous liquid in its passage from the chamber back to the reservoir. To further avoid any tendency for such choking of the oil, the overflow pipe is preferably free from any sharp turns and is so arranged that a vented communication is maintained between the chamber within the Y 45 and the atmosphere through the overflow pipe, reservoir and vent pipe. By this means, not only is there a substantially

constant level of oil maintained at all times in the elevated chamber, but a substantially unvarying pressure is maintained on the oil in the supply pipe.

5 Between the elevated supply chamber and the burner there is provided in the oil line a valve 53 through which the supply of oil to the burner may be varied if required.

The electric motor 51 is employed not only 10 to drive the oil pump 35, but also a pressure creating device, such as the air pump 55, which feeds air to the burner through the air pipe 17, the latter having adjacent the blower the air gauge 57 and means, such as 15 the relief valve 59, whereby the air pressure may be regulated.

In order to prevent the supply of oil to the burner except when air under the required pressure is supplied through the air supply 20 pipe 17 but to permit such oil supply when the air pressure is adequate, there is provided in the oil supply pipe 11 an oil cut-off valve, the lever for which is shown at 61, so arranged that it closes whenever the pressure 25 in the air supply pipe drops below a predetermined amount but opens when the air pressure rises to the required point. For this purpose the valve lever 61 is connected by the chain 63 to the end of an arm 65 30 (see Fig. 2), the latter pivoted at 67. The arm rests through a knife edged connection 69 on the end of a vertically movable rod 71. The lower end of the latter is connected to a plate 73, the under side of which is exposed 35 to air pressure from the pipe 17 through the connection 75 but is normally depressed by the corrugated or bellows-like metallic connection 77. The end of the valve lever 61 is weighted to normally close 40 the valve, and one end of the lever arm 65 has the weight 79, the weight being so adjusted that when the air pressure in the pipe 17 reaches the required point the plate 45 lifts against the resiliency of the corrugated connection 77, swinging the lever arm 65 about its pivot 67 to the dotted line position shown, arresting the valve arm 61 and thereby opening the oil supply valve. The latter 50 remains open so long as the necessary air pressure is maintained, but as soon as the latter ceases or drops below the required amount the elastic connection 77 forces the plate 73 down, allowing the weighted lever 55 60 61 to fall and close the oil valve. The oil supply is therefore promptly shut off as soon as the air supply falls from any cause and any tendency of the oil flow to persist is stopped. This prevents the oil from reaching the burner before sufficient air pressure has been 65 built up to properly atomize the oil and also

prevents the oil from backing up through the air supply pipe. At the same time it permits the oil to be fed under the desired pressure established by the elevated supply chamber the moment that the air pressure 65 has reached its required point.

The described devices may be employed in conjunction with the usual devices for automatically starting and stopping the motor 70 51 under the control of thermostat apparatus, the latter responsive to the pressure of the space to be heated and to the pressure of steam in the heater and to the presence or absence of the flame at the pilot light, but, as these devices are well known, they 75 are not herein illustrated.

While I have herein shown for the purposes of illustration one specific embodiment of the invention, it is to be understood that the same is submitted for the purposes of 80 illustration and that the details of construction and relative arrangement of parts, as well as the application of the invention, may be varied within wide limits without departing from the spirit thereof. 85

Claims:

1. In a liquid fuel burning apparatus, the combination with a burner, of a fuel supply conduit, a supply chamber elevated above the burner, a vented reservoir, means for supplying fuel to the chamber from the reservoir in excess of the requirements of the burner, said chamber having an overflow conduit extending laterally and downwardly at an inclination to the vertical from said 90 chamber to said reservoir, the overflow conduit having a capacity in excess of that required for the maximum overflow, and providing an air vent passage from the reservoir to the chamber. 95

2. In a liquid fuel burning apparatus, the combination with a burner, of a fuel supply conduit, a Y-connection providing a supply chamber elevated above the burner, a vented reservoir, a pump for supplying fuel to the chamber from the reservoir in excess of the requirements of the burner, an overflow pipe connected to one branch of the Y extending laterally and downwardly to the reservoir, said pipe having a capacity in excess of the 105 pump, thereby to maintain a substantially constant level in the chamber and a substantially unvarying pressure on the oil in the supply conduit under all conditions of burner operation, said pipe line providing an 110 air vent for said chamber. 115

In testimony whereof, I have signed my name to this specification.

ARTHUR H. BALLARD.
